Lawrence H. Stowell
BY HIS ATTORNEY
James F. Williamson

UNITED STATES PATENT OFFICE.

LAWRENCE H. STOWELL, OF WHEATLAND, NORTH DAKOTA.

GRAIN HOLDER FOR BINDERS.

1,424,122.

Specification of Letters Patent. Patented July 25, 1922.

Application filed November 10, 1920. Serial No. 423,084.

To all whom it may concern:

Be it known that I, LAWRENCE H. STOWELL, a citizen of the United States, residing at Wheatland, in the county of Cass and State of North Dakota, have invented certain new and useful Improvements in Grain Holders for Binders; and I do hereby declare the following to be a full, clear, and exact description of the invention, such as will enable others skilled in the art to which it appertains to make and use the same.

This invention relates to a grain holder for binders, and particularly to a holder which is disposed on the sheaf forming deck of a binder. It has been the practice heretofore to hold the head end of the sheaf on this deck by means of a pair of depending spaced wires or light rods disposed in the slot in the grain deck through which the binding and packing members operate, or by upwardly projecting wires or rods. It has been found that such holding means does not operate efficiently to form the proper sheaf.

It is an object of this invention, therefore, to provide a grain holding means for the head end of the sheaf which will insure that a compact and even sheaf is formed.

It is a further object of the invention to provide such a device which can be readily attached to a standard binder without any serious change therein. These, and other objects of the invention will become apparent as the description proceeds in connection with the accompanying drawings, in which like reference characters indicate the same parts throughout the different views, and in which—

Fig. 1 is a perspective view showing the invention as applied to a binder, the greater part of which is shown in dotted lines; and

Fig. 2 is a perspective view of the device showing the grain deck in section and the trip position of the device in dotted lines.

Referring to the drawings, in Fig. 1 is illustrated a binder of standard design having the grain deck or board *a*, the butter *b*, and a packer *c*. A trip bar *d* which is disposed in a central slot in the grain deck and which carries a grain and twine holding arm *e* is also shown in Figs. 1 and 2, and this bar is adapted to be oscillated at intervals when the sheaf is discharged, to swing the arm *e* downwardly into position

below or into substantial parallelism with the deck.

The device of the invention comprises an arm 1 which extends laterally from the trip bar *d* referred to, and is preferably disposed beneath the grain board or deck *a*. Elongated slots 2 are formed in the deck and suitably spaced to receive pins or rod-like members 3 which project upwardly from the bar 1. The bar 1 is illustrated as being somewhat flattened at its outer end, and at its other end is formed with an attaching flange or plate extending at right angles to the same and provided with bolt holes 4 to accommodate the fastening bolts which secure it to the said trip bar. It will, of course, be understood that the bar 1 may be of any suitable shape, and while three of the pins 3 have been shown, this number may be varied, as desired. While it has been found convenient to attach the member 1 to the trip bar *d*, which is present in practically all types of binders, it can, of course, be attached to any oscillating member which will be found convenient to swing it to its desired positions. The slots 2 are made of sufficient length to accommodate the motion of pins 3 when the sheaf is being formed, and said pins are projected upwardly through the deck, as shown in full lines in Figs. 1 and 2, and when the sheaf is to be discharged, the same will be swung downwardly to substantially the position shown in dotted lines in these figures, so that the sheaf can be readily discharged thereover.

The pins 3 form a firm support for the heads of the grain as the sheaf is being formed and the stalks are prevented from slipping downwardly toward the head end as the butts are packed into position by the butter *b*. The device, therefore, co-operates with the grain packers and the butting member to form a sheaf in which the heads are evenly disposed and one which can be securely bound and be subsequently handled without the grain becoming loosened or without being distorted.

It is thus seen that applicant has produced a simple attachment for a binder, the use of which greatly improves the formation of the sheaf. It will, of course, be understood that various changes may be made in the form, size and details of the device without

departing from the scope of the invention, which, generally stated, consists in the matter shown and described and set forth in the appended claims.

5. What I claim is:

1. A grain holding device for a binder adapted to be disposed on the head side of the sheaf supporting grain deck thereof, which comprises spaced members extending upwardly from the surface of said deck.
10. 2. A device of the class described, comprising a plurality of spaced rod-like members extending upwardly from the head side of the sheaf forming deck of a binder, a supporting means for said members, and means for attaching said first mentioned means to a trip member of a binder whereby said rod-like members will be swung downwardly to sheaf discharging position.
15. 3. The combination with a sheaf forming deck, and sheaf forming members of a grain binder, a grain holding device comprising a bar extending longitudinally beneath said deck, spaced pins thereon extending upwardly through slots in said deck, and means for swinging said pins to and from sheaf discharging position.
20. 4. An attachment for a grain binder com-

prising a bar adapted to extend longitudinally of the sheaf forming deck of a binder, spaced pins extending at right angles thereto and adapted to project upwardly from the said grain deck, attaching means on said bar for attaching the same to a swinging member of a binder.

35. 5. The combination with a sheaf forming deck and sheaf forming members of a binder, of means for rigidly holding the heads of the sheaf as the same is formed, and means for swinging the same to sheaf discharging position.

6. In combination with the sheaf-forming means of a binder including the sheaf holding members and packers, an auxiliary sheaf holder comprising spaced pins projecting upwardly from and through the grain deck of the binder at one side of the slot in said deck in which the grain-forming and tieing devices operate.

In testimony whereof I affix my signature 50 in presence of two witnesses.

LAWRENCE H. STOWELL.
